UNITED STATES PATENT OFFICE

GARRETT W. MUDD, OF CHICAGO, ILLINOIS, ASSIGNOR TO MANUFACTURERS MACHINERY COMPANY, OF CHICAGO, ILLINOIS, A CORPORATION OF ILLINOIS

FEEDING MECHANISM FOR INTERLACING MACHINES

Application filed September 4, 1928. Serial No. 303,940.

This invention relates to improvements in feeding mechanism particularly adapted, though not necessarily limited in its use with machines for interlacing hair, fibers and the like, and one of the objects of the invention is to feed the material and evenly distribute the same into the interlacing machine, whereby a pad of uniform thickness and density will be provided.

10 A further object is to provide an improved machine of this character embodying a delivery or discharge spout or nozzle and improved means for vibrating or oscillating the nozzle, during the delivery or discharge 15 of the material therefrom, the material being delivered into and from the nozzle by centrifugal force.

To the attainment of these ends and the accomplishment of other new and useful objects 20 as will appear, the invention consists in the features of novelty in substantially the construction, combination and arrangement of the several parts hereinafter more fully described and claimed and shown in the accompanying drawings illustrating this invention, and in which—

Figure 1 is a vertical, sectional view taken on line 1—1, Figure 3.

Figure 2 is a sectional view taken on line 30 2—2, Figure 1.

Figure 3 is a view taken on line 3—3, Figure 1.

Referring more particularly to the drawings the numeral 10 designates a casing of any 35 desired size and configuration, within which is arranged a rotary member 11 having projections 12 and which casing is provided with an inlet opening 13 and a discharge outlet 14. The casing 10 is preferably of a considerable 40 length as is also the rotary member 11, the outlet 14 extending throughout the length of the casing so as to provide an extended comparatively narrow outlet. Connected with this outlet is a discharge tube prefer- 45 ably divided into two branches 15, the

branches preferably increasing in height toward the outlet ends 16 thereof so that material discharged through the outlet opening 14 will be delivered simultaneously into both of the pipes or passages 15.

Connected to the free end of each of the tubes 15 is a spout or nozzle 17, adapted for a swinging movement with respect thereto. Each of these nozzles is curved downwardly and depends for a considerable distance below the outlet, and is shaped to form a concaved wall against which the material being delivered thereto strikes. This will cause the material to follow the central portion of the wall as it is delivered into the chute and prevents whipping of the material as the nozzle is oscillated. The extremities of the nozzles preferably project into and move within a hopper or receiver 19. One face of the lower end of each of the nozzles is preferably cut away as at 20 so as to permit air which may be carried with the material through the nozzle to be separated therefrom and escape.

The material may be fed into the casing 10 in any suitable manner such as by means of a conveyor 21 and from the conveyor the material passes between two rollers 22—23, respectively provided with ribs or projections 24—25 to assist in conveying the material and to partially disintegrate the same. When the material is passed between the rollers 22—23 it is delivered into the inlet opening 13 of the casing and will then be caught by the ribs or projections 12 on the rotary element 11 and forced by centrifugal force to and through the discharge outlet opening 14.

During the time that the material is being conveyed by the element 11, it will be disintegrated, and the element 11 will throw the material by centrifugal force through the discharge opening 14 into the tubes or passages 15 through the delivery end thereof into the spouts or nozzles 17. The material will be deflected downwardly through the

nozzles into the container 19 and as the material leaves the nozzle the air, if any is carried with the material, will escape through the cut away portion 20 into the atmosphere.

5 The element 11 may be driven in any suitable manner from a suitable source of power (not shown) by means of a belt 26 and the rollers 22-23 may also be driven in any suitable manner preferably from the shaft 27 of the element 11, through the medium of a belt 28 that passes over a pulley 29 on a shaft 30. Connected also with the shaft 30 10 may be a pulley 31 over which a belt 32 passes, and this belt in turn passes over a pulley 33 on the shaft 34 of the roller 22, the rollers 22 and 23 being connected together in any suitable manner so that one 15 will be operated by the other.

20 As the material is delivered through the spouts or nozzles 17 and in order to evenly distribute the material within the receptacle or container 19 so as to produce a pad of uniform thickness and density, an oscillating or swinging movement is imparted to the nozzles 17 with respect to the tubes or passages 15. To that end the nozzles 17 may be connected together by means of a suitable connecting rod 35 hingedly connected as at 36 to arms or projections 37 depending below the nozzles.

25 A bell crank lever 38 is pivotally mounted as at 39 to a suitable support 40. One arm of the lever is connected by means of a link 41 with the bar or connection 35 and to the other arm of the lever is connected one end of a link 42. The other end of the link 42 is connected with a member 43 provided with a slot 44 through which the shaft 30 passes. 30 Mounted upon the member 43 is a roller 45 which operates in a groove 46 of a cam member 47. The cam member is secured to the shaft 30 for rotation therewith so that when the shaft 30 is rotated the cam member 47 35 will be correspondingly rotated and the bell crank lever 38 will be rocked to impart a swinging movement to the nozzles or spouts 40 17.

Obviously the groove 46 in the cam may 45 be of any desired configuration to impart the desired movement to the nozzle 17.

While the preferred form of the invention has been herein shown and described, it is to be understood that various changes may 50 be made in the details of construction and in the combination and arrangement of the several parts, within the scope of the claims, without departing from the spirit of this invention.

55 What is claimed as new is:—

1. Means for feeding hair to and distributing the same in an interlacing machine embodying a casing having an inlet for the material, a discharge outlet from the casing 60 having two spaced delivery openings, down-

wardly curved extended delivery spouts individual to said outlets and swingingly supported with respect thereto, cam means common to said spouts for imparting a swinging movement to said spouts in unison for distributing the material with respect to the interlacing machine, and means within the casing for disintegrating the material and for throwing the same through said outlets by centrifugal force. 70

2. Means for feeding hair to and distributing the same in an interlacing machine embodying a casing having an inlet for the material, a discharge outlet from the casing having two spaced delivery openings, downwardly curved extended delivery spouts individual to said outlets and swingingly supported with respect thereto, said spouts having concaved walls in alignment with the outlet means common to said spouts for imparting a swinging movement to said spouts in unison for distributing the material with respect to the interlacing machine, means within the casing for disintegrating the material and for throwing the same through 80 said outlets by centrifugal force, and means for feeding the material into said casing through the said inlet. 90

3. Means for feeding hair to and distributing the same in an interlacing machine embodying a casing having an extended discharge outlet shaped to form two separated delivery openings, means within the casing for disintegrating the material and for throwing it simultaneously through both of 100 said openings by centrifugal force, and nozzles individual to said openings and connected with the respective outlets for free swinging movement with respect thereto to distribute the material in the interlacing machine, said nozzles being curved downwardly and spaced from each other, the wall of the nozzles against which the material strikes as it enters the downwardly curved portion being concaved, one side of each of 105 the nozzles being cut away to permit air which may be carried by the material to escape from the nozzle independently of the material being delivered therethrough. 110

4. Means for feeding hair to and distributing the same in an interlacing machine embodying a casing having an extended discharge outlet shaped to form two separated delivery openings, means within the casing for disintegrating the material and for throwing it simultaneously through both of 120 said openings by centrifugal force, nozzles individual to said openings and connected with the respective outlets for free swinging movement with respect thereto for distributing the material in the interlacing machine, said nozzles being curved downwardly and spaced from each other, said nozzles depending for a considerable distance, the wall 125 of the nozzle against which the material 130

strikes as it enters the nozzle being concaved, one side of each of the nozzles being cut away to permit air which may be carried with the material to escape from the nozzle independently of the material being delivered therethrough, and means common to said nozzles for swinging them back and forth in unison.

5 In testimony whereof I have signed my name to this specification, on this 15th day of August, A. D. 1928.
